UNITED STATES PATENT OFFICE.

CHARLES H. MACDONALD, OF MONTCLAIR, NEW JERSEY, ASSIGNOR, BY MESNE ASSIGNMENTS, TO IVERS-LEE COMPANY, OF NEWARK, NEW JERSEY, A CORPORATION OF DELAWARE.

PACKAGE.

Application filed June 7, 1919, Serial No. 302,548. Renewed October 30, 1924.

To all whom it may concern:

Be it known that I, CHARLES H. MACDONALD, a subject of Kingdom of Great Britain, residing in Montclair, in the county 5 of Essex and State of New Jersey, have invented an Improvement in Packages, of which the following is a specification.

The present invention relates to an improvement in packages, more particularly of 10 the kind adapted to contain products readily segregated as units, such as medicinal preparations or other chemical or edible articles in tablet or similar form, small articles of hardware, buttons and various other relatively small articles.

One of the principal objects of this invention is to provide a package which will afford an effective covering for articles of the character referred to and others, not 20 only to protect such articles from dust, dirt and the like, but also, where the articles are soluble, to exclude moisture from contact therewith so that they may be transported or carried in stock without deterioration.

25 The invention also, so far as it relates to a process or method, is intended to provide a sequence of operations in accordance with which a suitable package of the character described may readily be formed.

30 One form of package embodying my invention is illustrated in the drawings accompanying the present specification, said drawing also serving to illustrate a typical application of my improved method of making one form of package embodying my invention. In the drawings,

Figure 1 is a plan view of a web of material with spaced articles in position thereon,

35 Figure 2, a plan view of the same or a similar web with the marginal portions folded to inclose articles and with the portions between the articles stiffened and pressed into adhering contact.

40 Figures 3 and 4 are longitudinal and transverse vertical sections respectively of a portion of the package illustrated in Figure 2.

In practicing the method forming a part 45 of the present invention, a strip 1 of flexible material, preferably paper, having a coating of paraffin on at least one side and, with the articles to be packaged arranged thereon in spaced relation may be folded longitudinally to form a tubular container with con-

tinuous closed edges adapted to inclose articles 2, the folding being accomplished in such a manner that the interior surface will be paraffined and the inclosed articles arranged in spaced relation. Pressure may 60 then be applied to the tubular container between the spaced articles in such a manner as to form adhering or sealing stiffened portions 3. One convenient way to accomplish this sealing and stiffening is to crimp the 65 tube transversely, a suitable type of crimping being shown in Figure 2 of the drawing.

In pursuing the method hereinabove described, a package is produced in which spaced articles are inclosed in a container 70 having adhering or interlocking stiffened portions 3, formed either by crimping or otherwise pressing opposed interior portions into intimate adhering contact, between each two adjacent articles, said 75 stiffened portions serving not only to space the articles but also when the strip is bent transversely with spacing portions interposed flatly between articles carrying compartments, to protect the articles from break- 80 age. In manufacture this stiffening also enforces bending of the strip at unstiffened portions thereof, or across the compartments if desired, thus facilitating the forming of packages having the article carrying compartments arranged in zigzag or stacked relation and separated by interposed spacing portions. The spacing portions are preferably of substantial extent or area in proportion to the size of the compartments so 85 that the strip may be gripped manually or otherwise across the stiffened spacing portion during the detaching of a unit or units from the package to prevent unsealing or exposure of the next succeeding unit. 95

In using packages embodying my invention, or made in accordance with the method hereinabove set forth, the consumer or user may detach a single article simply by tearing or cutting the material adjacent to said article, and without exposing the article next in succession. This form of package for many articles presents advantages in use over packages heretofore commonly used, not only in the additional protection from dust 100 and moisture already referred to, but also in the facility with which such packages may be made, the inoffensive character of the materials of the package, and the compactness and durability thereof, all of which are de- 110

sirable qualities in packages intended for use with articles of various kinds.

I claim as my invention:

1. The method of packaging articles which includes coating a strip of flexible material with a plastic material arranging articles to be packaged on said strip in spaced relation, folding said strip longitudinally with a coated surface inside to enclose 10 said articles in spaced relation, and pressing opposed interior surfaces into adhering contact between the enclosed articles.
2. The method of packaging articles which includes enclosing a plurality of articles in spaced relation in a strip of paper having a coating of paraffin by folding over the longitudinal edges of said strip with the articles arranged thereon to form a tubular container, the coated surface of the strip 15 forming the interior surface of the container, and pressing opposed interior sur-

faces of said container into adhering contact to form article isolating portions between enclosed articles.

3. A package consisting of a strip of flexible material having a coating of paraffin on one side and with its longitudinal edges folded toward and overlapping each other to form an article carrying tube with a paraffin coated interior surface, said tube being provided at spaced intervals across its entire width with tube deforming crimpings extending lengthwise of the tube and through its walls to securely hold spaced portions of said walls in effective tube closing and sealing contact and to impart relative rigidity to said tube closing portions. 25

In testimony whereof, I have signed my name to this specification this 3rd day of June, 1919.

CHARLES H. MACDONALD.
